UNITED STATES PATENT OFFICE

106,401

DESIGN FOR A DRESS

David William Price, New York, N. Y.

Application August 12, 1937, Serial No. 71,018

Term of patent 3½ years

To all whom it may concern:

Be it known that I, David William Price, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The sleeves have open work embroidery on their outer and lower edge portions, as shown.

The irregularly curved seam below the front shoulder line, extends to the sleeve seam, terminating in a tuck.

I claim:

The ornamental design for a dress, substantially as shown, and described.

DAVID WILLIAM PRICE.
